CLAIM

The ornamental design for a perfume container, as shown and described.

DESCRIPTION

FIG. 1 is a perspective view from above of a perfume container according to a first embodiment;

FIG. 2 is a front view of the perfume container of FIG. 1; FIG. 3 is a rear view of the perfume container of FIG. 1; FIG. 4 is a side view of the perfume container of FIG. 1, the view from the opposite side corresponds;

FIG. 5 is a top view of the perfume container of FIG. 1; FIG. 6 is a bottom plan view of the perfume container of FIG. 1;

FIG. 7 is a cross-section view of the perfume container of FIG. 1 along the line 7-7 shown in FIG. 2;

FIG. 8 is a cross-section view of the perfume container of FIG. 1 along the line 8-8 shown in FIG. 2 thereof;

FIG. 9 is a perspective view from above of a perfume container according to a second embodiment;

FIG. 13 is a top view of the perfume container of FIG. 9; FIG. 14 is a bottom plan view of the perfume container of FIG. 9;

The broken lines in the drawings depict portions of the perfume container that form no part of the claimed design.
